CLAIM

The ornamental design for a sign, as shown and described.

DESCRIPTION

FIG. 1 is a front elevational view of a sign showing our new design, the broken line disclosure of indicia being for illustrative purposes and forming no part of the claimed design;

FIG. 2 is a top plan view thereof;

FIG. 3 is a left end elevational view thereof;

FIG. 4 is a sectional view taken on line 4—4 of FIG. 1; and

FIG. 5 is an exploded perspective view from the rear, showing an indicia card of the sign being popped into one cell of a row strip of the sign, and the row strip being slid into the sign panel of the sign.

A bottom plan view of the sign would be a mirror image of FIG. 2; a right end elevational view thereof would be a mirror image of FIG. 3.
